[57] CLAIM

The ornamental design for a marking instrument, as shown and described.

DESCRIPTION

FIG. 1 is a front elevational view of a marking instrument showing my new design;

FIG. 2 is a rear elevational view;

FIG. 3 is a left side elevational view;

FIG. 4 is a right side elevational view;

FIG. 5 is a top plan view;

FIG. 6 is a bottom plan view; and

FIG. 7 is a perspective view of my design in an exploded condition.
